D. P. McLAUGHLIN

CUTTING DEVICE

Filed March 4, 1926

INVENTOR.
DENIS P. McLAUGHLIN

BY *A. B. Bowman*
ATTORNEY

UNITED STATES PATENT OFFICE.

DENIS P. McLAUGHLIN, OF SAN DIEGO, CALIFORNIA.

CUTTING DEVICE.

Application filed March 4, 1926. Serial No. 92,190.

My invention relates to cutting devices, particularly adapted for cutting column rules for printing newspapers or other printed matter.

The objects of my invention are: first, to provide an efficient device of this class for cutting column rules or the like by a short stroke and light blow of the hand and whereby unnecessary movement and waste of energy are eliminated; second, to provide a device of this class whereby only limited thicknesses of material may be cut and such thicknesses of material as are employed in making column rules; third, to provide a device of this class whereby the column rules or other similar strips of material may be easily inserted between the cutting members from the front side of the device with its one end against the measuring stop means; fourth, to provide a device of this class having an inclined table for supporting the material to be cut and a square-edged cutting member, whereby the cutting members may be made and cut from a long bar of the required cross-section; fifth, to provide a device of this class in which the cutting members may be easily changed; sixth, to provide as a whole a novelly constructed hand-operated impact cutting device for cutting column rules and the like; seventh, to provide a device of this class which is particularly simple and economical of construction, durable, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a front side view of my cutting device; Fig. 2 is an end view thereof; Fig. 3 is a partial sectional and partial plan view thereof, with the section taken at 3-3 of Fig. 1; Fig. 4 is a fragmentary end elevational view thereof, taken from the opposite end of the device and on the line 4-4 of Fig. 1, and Fig. 5 is a fragmentary sectional elevational view thereof, taken through 5-5 of Fig. 3.

Like characters of reference refer to simi-

lar parts and portions throughout the several views of the drawings.

The main support of my cutting device consists of a base member 1 having supporting legs at its opposite ends, cutting members at its one end and a measuring stop or gage intermediate its ends. At the upper side of the base member 1 is provided a backwardly and downwardly inclined supporting surface 1^a upon which the column rules, or other material to be cut, are positioned. At the back side of the supporting surface is provided an upwardly extending ledge 1^b which serves as a back stop and at the upper side of which is inscribed or otherwise appropriately applied a measuring scale 1^c which, for cutting column rules, is graduated into picas, as shown. At the one end of the base member is a yoke 1^d, which extends upwardly from the supporting surface of the base member and forwardly from the back ledge thereof. This yoke consists of a pair of upright members, the one positioned forwardly from the other and connected with each other by means of horizontal cross portions 1^e. The forward upright member of the yoke is spaced upwardly from the supporting surface 1^a of the base member providing a clearance, indicated by 1^f in Figs. 2, 4 and 5, to permit the insertion of the column rules or other members to be cut between the cutting members of the device from the front side thereof.

At the one end of the base member, below the yoke, is secured, by means of pins 3 and screws 4, a cutting member or plate 2. This cutting member is laterally positioned in a slot at said one end of the base member. Said cutting member is beveled at its upper edge downwardly toward the supporting surface of the base member and is positioned with its keen cutting edge a slight distance above the supporting surface of the base member, as shown best in Fig. 5. The forward end of the cutting edge is beveled backwardly so as to provide ready insertion of the column rules or other members to be cut into the clear space 1^f between the lower end of the yoke and the cutting member 2.

On the cross portions 1^e of the yoke 1^d is reciprocally mounted a plunger rod 5, which extends through said portions and is provided at its upper end with a knob 6 and at its lower end with a cutting member 7,

said plunger rod being screwed at its lower end into said cutting member and retained in position thereon by means of a set screw 8. The knob 6 serves as a means for forcing 5 the cutting member 7 downwardly as well as the stop at its lower end against the upper cross portion 1^e of the yoke. The cutting member 7 is reciprocally mounted in a vertical direction in a slotted portion 1^g at 10 the lower end of the yoke. Said cutting member 7 is retained in position in the slotted portion of the yoke by means of a pair of plates 9 and 10 secured, by means of screws 11, to the outer side of the yoke at 15 the end of the base member. Around the plunger rod 5 and between the cross portions 1^e of the yoke is positioned a compression spring 12, which bears at its upper end against the lower end of a collar 13 secured 20 to the plunger rod intermediate the cross portions 1^e of the yoke and normally forces the cutting member 7 and the knob 6 in their respective upper positions.

The lower portion of the cutting member 25 7 is beveled upwardly and outwardly, forming a cutting edge directly over the cutting edge of the member 2. The cutting edge of the member 7 is perpendicular with the attached operating plunger rod 5, thus permitting the cutting member 7 to be made 30 from a long cutting bar, which may be carried in stock and readily cut and fitted to the cutting device for replacing the cutting member 7.

35 Over the supporting surface of the base member is positioned a measuring stop member 14, which is provided at its rear portion and lower side with a guide slot 14^a for receiving the back ledge 1^b of the base member 40 upon which the member 14 is guided. Through the rear end of the stop member 14 extends a thumbscrew 15 for securing the stop member in various adjusted positions relatively to the base member against 45 the side of which adjacent the cutting members the one ends of column rules or other members to be cut may be positioned for cutting said column rules or other members to even lengths.

50 Though I have shown and described a particular construction, combination and arrangement of parts and portions, I do not wish to be limited to this particular construction, combination and arrangement, but 55 desire to include in the scope of my invention the construction, combination and arrangement substantially as set forth in the appended claims.

Having thus described my invention, what 60 I claim as new and desire to secure by Letters Patent is:

1. In a device of the class described, a base member having a backwardly and downwardly inclined supporting surface at its upper side and an upwardly extending ledge

at the rear portion of said supporting surface, said base member having a cutting edge forwardly of said ledge, and a cutting member reciprocally supported by said base member with its cutting edge normally positioned above the cutting edge of said base member and inclined with respect thereto. 70

2. In a device of the class described, a base member having a backwardly and downwardly inclined supporting surface at 75 its top side and an upwardly extending ledge at the rear portion of said supporting surface, said base member having a cutting edge positioned forwardly of and substantially parallel with said supporting surface, said base member also having a yoke above said cutting edge and spaced at its lower end above the supporting surface from said upwardly extending ledge to the front side of the device, a plunger rod reciprocally mounted in said yoke, a cutting member secured to the lower end of said rod with its cutting edge positioned above the cutting edge of said base member and inclined relative thereto, an impact knob secured to the upper end of said rod and serving as a stop against the upper end of said yoke, and a compression spring positioned around said rod intermediate the ends of said yoke for normally separating said cutting members. 85

3. In a cutting device of the class described, a base member having a backwardly and downwardly inclined supporting surface at its upper side and a rear upwardly extending ledge at the rear portion of said supporting surface, said base member having a cutting edge at its one end, a cutting member reciprocally mounted at the one end of said base member with its cutting edge above said first mentioned cutting edge and inclined relative thereto, a knob connected to said cutting member and extending thereabove for manually forcing said cutting member downwardly by impact, and an adjustable stop member reciprocally mounted on said upwardly extending ledge above the supporting surface of said base member. 100 105 110

4. In a cutting device of the class described, a base member having a backwardly and downwardly inclined supporting surface at its upper side and a rear upwardly extending ledge at the rear portion of said supporting surface, said base member having a cutting edge at its one end, and a cutting member reciprocally mounted at the one end of said base member with its cutting edge above said first mentioned cutting edge and inclined relative thereto, said cutting edge at the one end of said base member extending slightly above the supporting surface thereof, there being provided clearance at the forward portion of said base member between the cutting edge thereof and the cutting edge of said cutting member to 115 120 125 130

permit insertion of material to be cut from the front side of the device between the cutting edges of said base member and said cutting member.

5. In a device of the class described, a base member having a backwardly and downwardly inclined supporting surface at its top side and an upwardly extending ledge at the rear portion of said supporting surface, a cutting member secured at the one end of said base member and provided with a cutting edge at its upper end, said cutting edge extending slightly above the supporting surface of said base member, said base member having a yoke at its one end extending above said cutting member and spaced at its lower end above said supporting surface from said upwardly extending ledge to the front side of the device, a plunger rod

reciprocally mounted in said yoke, a cutting member removably secured to the lower end of said rod with its cutting edge positioned above the cutting edge of said first mentioned cutting member, an impact knob secured to the upper end of said rod and serving as a stop against the upper end of said yoke, a compression spring positioned around said rod intermediate the ends of said yoke for normally separating said cutting members, and an adjustable stop member mounted on the upwardly extending ledge of said base member and securable thereto, said stop member being positioned above said supporting surface.

In testimony whereof, I have hereunto set my hand at San Diego, California, this 24th day of February, 1926.

DENIS P. McLAUGHLIN.
